UNITED STATES PATENT OFFICE.

AARON APPEL, OF CHICAGO, ILLINOIS.

MARKING-TAG.

SPECIFICATION forming part of Letters Patent No. 319,543, dated June 9, 1885.

Application filed November 17, 1884. (No model.)

To all whom it may concern:

Be it known that I, AARON APPEL, of Chicago, in the county of Cook and State of Illinois, have invented certain new and useful 5 Improvements in Marking-Tags; and I do hereby declare that the following is a full, clear, and exact description thereof, reference being had to the accompanying drawings, and to the letters of reference marked thereon, 10 which form a part of this specification.

The object of this invention is to provide an improved construction in price-tags, whereby they may be conveniently attached flat upon the surface of a piece of cloth or upon the exposed edges of bolts of cloth or folded garments.

The tag herein shown, illustrating this invention, is adapted for use in connection with an ordinary pin as a fastening device; and it 20 consists of a tag provided with a passage for the pin parallel with the face of the tag, adapted for the insertion of the pin, the tag being secured to the cloth by inserting the pin first through a narrow fold of the cloth, then 25 through the passage of the tag, and then engaging the point of the pin again with the cloth. By this means the pin is engaged with the cloth at both its ends and with the tag at its middle portion, so that the tag is held 30 closely and firmly against the cloth. The tag preferably consists of an upper flat layer or thickness of paper or card-board, upon which the designation marks, signs, or other characters are to be placed, and a lower or inner 35 layer of paper, which is unattached to the upper layer, along a narrow space crosswise of the tag, where it is outwardly bent or made in loop form, so as to form the transverse aperture or passage referred to, through which the 40 pin may be inserted. The upper layer in this construction is also usually made of relatively stiff material, so that when the pin is inserted it will lie perfectly flat. The upper and lower layers comprising the tag may, 45 however, be separated by a third layer of card-board, of approximately the thickness of a pin, a part of said third layer being removed, so as to form a transverse passage for the pin. In this case both the upper and 50 lower surfaces of the tag will obviously be flat. In any case the lower layer, which forms

the transverse loop for the pin, may be of less width than the upper or top layer of the tag, so that when the latter is used with a pin which is shorter than the width of the tag 55 along the pin-passage the head and point of the pin will be entirely concealed beneath said top layer. Instead of making the tag in layers, it may be molded from pulp, and thus consist of only a single piece.

60 The invention may be more fully understood by reference to the accompanying drawings, in which—

Figure 1 is a perspective view of a tag constructed in accordance with my invention, said tag being shown as secured upon the surface of a piece of cloth by means of a common pin. Fig. 2 is a plan view of the same. Fig. 3 is a cross-section through the tag and cloth, taken upon line *x x* of Fig. 2. Fig. 4 is a similar 70 section taken upon the line *y y* of Fig. 2. Fig. 5 is a perspective view from beneath of a form of tag in which the loop for the pin is made narrower than the tag proper, in order to admit of the head and point of the fastening-pin 75 being concealed beneath the tag. Fig. 6 is a transverse section of the tag shown in Fig. 4. Figs. 7 and 8 are sectional views illustrating 80 a form of tag in which both the surfaces of both upper and lower layers are flat.

85 As illustrated in the drawings, A is a tag, which is usually composed of two layers, A' A'', of paper, pasteboard, or other suitable material, which are pasted, glued, or otherwise secured together. The said tag is provided with a transverse aperture, *a*, formed between the layers A' A'', which aperture is parallel with the surface of the tag, and is adapted for the insertion of a straight fastening-pin, B. (Herein shown as in the form of 90 a common headed pin.)

95 As shown in Figs. 1, 2, 3, 4, 5, and 6, the aperture *a* is formed by an outward fold or bend in the lower layer, A'', of the tag, said lower layer preferably being made relatively thin and flexible, while the upper layer, A, is relatively thick and stiff, so as to form a flat surface upon which the marks or characters suitable for the purposes of the tag may be conveniently written.

100 In fastening the tag to the cloth the pin is caught in the cloth at either end of the pas-

sage *a*, as indicated at *b b'*, and is engaged with the tag at its middle portion. In Figs. 5 and 6, the under or bottom layer, *A*², is shown in the form of a strip narrower than the width 5 of the tag, which is pasted at its end portions to the upper layer, *A'*, and is made in loop form at its middle to form the pin-passage *a*. When the tag is constructed as last described, and as clearly shown in Fig. 6, a pin may be 10 used which is shorter than the width of the tag, so that when engaged with the cloth at its ends its head and point will be concealed beneath the tag.

In the tag shown in Figs. 7 and 8 the upper 15 and lower layers, *A'* and *A*², thereof are both perfectly flat, and the passage *a* is formed by means of a third layer or filling, *a'*, inserted in two parts between the layers *A'* and *A*², and pasted to the latter, a space being left between the two parts of the filling along a line 20 across the middle of the tag, so as to form the passage for the pin.

It is to be understood that in any case the tag may be either circular, rectangular, or of 25 any other desired shape.

To facilitate the application of the tag or the insertion of the fastening-pin into the passage *a*, any surface-mark may be printed or otherwise placed on the outer face of the tag to indicate the location of the passage *a*, or the edge of the tag may be nicked or notched slightly opposite the pin-passage, as indicated at *c*, Fig. 2; or any other suitable means for the same 30 purpose may be employed.

A tag composed of two layers of paper or 35 card-board, one layer consisting of a relatively hard material forming the outer face of the tag, and another under or inner layer formed of material of a porous or spongy texture, through which a pin may be readily inserted, 40 may be advantageously used instead of a tag with an open passage formed through it, as above described. It is to be understood, there-

fore, that a construction in which such spongy or porous layer of paper is used is within the 45 scope of my invention.

I claim as my invention—

1. An improved marking-tag comprising a flat top layer and an under layer provided with a depression or groove forming a straight 50 pin-receiving passage across the middle of the tag, combined with a removable straight fastening-pin adapted to pass through said passage, and when thus applied to extend beyond both ends of the passage, to admit of its engagement with the material upon which the tag is secured, substantially as described. 55

2. An improved marking-tag comprising a flat top layer and an under layer provided with a depression or groove forming a straight 60 pin-receiving passage, said under layer being narrower lengthwise of the passage than the tag-body, combined with a removable straight fastening-pin adapted for insertion through the passage of the tag, said pin being longer than 65 the passage, but shorter than the width of the tag-body, so that when applied it may be concealed by the same, substantially as described.

3. An improved marking-tag comprising a flat tag-body having across its middle a loop 70 forming a straight transverse pin-receiving passage, which is parallel with the plane of the tag-body and of a less length than the width of the same, combined with a straight fastening-pin, which is longer than the passage and shorter than the width of the tag-body, said tag-body being provided with a notch, *c*, opposite one end of the pin-passage, 75 substantially as and for the purpose set forth.

In testimony that I claim the foregoing as 80 my invention I affix my signature in presence of two witnesses.

AARON APPEL.
